UNITED STATES PATENT OFFICE

2,164,508

METHOD OF MAKING A SIDING STRIP

George Arthur Fasold, Cincinnati, Ohio, assignor
to The Philip Carey Manufacturing Company,
a corporation of Ohio

Application August 24, 1933, Serial No. 686,491

3 Claims. (Cl. 154—2)

This invention relates to building materials and to method of making the same. It relates more especially to the kind of building material known as "siding strip", for example, slate-surfaced asphalt felt siding strip.

At the present time there is considerable popular demand for building material such as siding strip. Siding strip is a preformed sheet building covering adapted to be secured in place on a wall in overlapping units so as to give the appearance of a brick wall, for example. To this end, along one margin of the units there is a coating of an adherent colored material such as colored slate granules of substantially uniform width. This 10 marginal strip of colored material contains at intervals cut out parts dividing the marginal granular colored material into lengths corresponding to the usual length of building bricks, for example, the width of the cut out portions 15 corresponding to the usual distance by which bricks are spaced by mortar placed between them. The remainder of the siding strip is of a color contrasting to that of the marginal coating and may be black, for example, in simulation of the 20 color of certain types of mortar. By securing a plurality of succeeding siding strips to a wall in overlapping relation so that the marginal colored coatings are spaced slightly from each other, the contrasting colors simulating brick faces and 25 mortar cause the completed wall to resemble a plurality of separate building bricks set in mortar.

Heretofore, siding strip has been made according to one method by first impregnating a web material such as felt with a bituminous saturant 30 and coating the impregnated web with a bituminous coating material to afford an adherent base for granular surfacing material. The web of material thus prepared has been coated uniformly with a granular material of a color (e. g., red) that is desired for the part of the strip designed to simulate brick. Thereafter a coating of asphaltic material has been coated over the granular material to afford a contrasting black color. The last coating of asphaltic material has 35 then been dusted with sufficient mica flakes, for example, to prevent the siding strip units from sticking together in shipment.

A difficulty arising in connection with the type of siding strip just described has been that the 40 coating of asphaltic material overlying the granular material does not lay evenly and does not produce an even and straight line of division between the portions of the strip contrasting in color. A further disadvantage has resulted from 45 the fact that the portion of the siding strip de-

signed to represent mortar has greater elevation on the siding strip with respect to the web base than the portion thereof designed to represent brick. Thus an optical effect is produced that is just the opposite of what is desired.

Heretofore siding strip has also been manufactured by distributing a colored granular material (e. g., designed to represent mortar) uniformly over a strip of saturated felt coated with bituminous coating material. Thereafter asphaltic material has been coated as with a roller along a margin of the strip overlying the layer of granular material first applied. Thereafter a granular material of a color designed to imitate brick has been applied to the strip so as to adhere here to the marginal asphaltic coating.

In the case of the type of siding last described as having been made heretofore, it has been found impossible to obtain a satisfactorily even and straight line of division between the coatings of contrasting colors due to the tendency of the asphaltic material to flow unevenly in being applied to the first coating of granular material. Another and even more serious difficulty has been that the weight of the two layers of material overlying the felt base has been so excessive that the marginal layer of asphalt and granules on the strip tends to slide very badly at summer temperatures. The two overlying layers of asphaltic material coated with granular material 20 overlying the felt base have frequently been found to exhibit as much as $\frac{1}{2}$ inch to 1 inch of slide with resultant unsightliness of the wall covered with the siding strip and impairment of its 25 weatherproofing properties.

It is a purpose of this invention to afford a siding strip wherein the difficulties heretofore encountered are overcome. In the practice of this invention it is possible to make siding strip wherein the line of demarcation between the portions of contrasting color is even and straight, wherein the portions simulating brick, for example, have greater elevation than the portion simulating mortar, and wherein no part of the strip is of such excessive weight as to cause undue sliding.

It is a feature of one embodiment of this invention that web material such as felt bituminized with bituminous saturating and coating material has adherently applied thereto one or more ribbons or strips of sheet material such as paper to the web. The exposed (upper) surface of the sheet material is preferably substantially non-adhesive in that granular or pulverulent material has little tendency to adhere thereto. The bituminized surface of the web base which is 50 55

not covered with the non-adhesive sheet material has applied adherently thereto a granular material of desired color.

The ribbons of paper or other sheet material that is used in manufacturing sheet building covering embodying this invention is preferably relatively thin so that the paper is substantially less thick than the coating of slate granules which is also adherent portions of the web base. Thus the granules have greater elevation with respect to the web base than the portions of strip covered with paper and a desired and natural appearing offsetting effect of portions simulating brick and portions simulating mortar is produced.

Since the ribbons of paper can be supplied with straight and even edges for application to the bituminized web base the line of demarcation between the portions of contrasting color can be made very even and straight affording a neat and attractive appearance when the siding strips embodying this invention are secured in place in normal overlapping relation on a wall.

It is apparent that in practicing this invention it is necessary to employ but one layer of coating material coated with granules while still producing desired effects of contrasting color. Thus, siding strip manufactured according to this invention is free from an uneven line of demarcation between portions of contrasting color and can be made so that the weight of material overlying the web base is so slight that the tendency of the strip to slide is reduced to a minimum.

It is important in the practice of this invention that the foregoing features are achieved while at the same time affording a siding strip in which the tendency to slide of the surface forming parts is substantially completely eliminated. In the co-pending application of Harold W. Greider and myself, filed July 20, 1933, Serial No. 681,286, which has now matured into Patent No. 2,105,531, dated January 18, 1938, for Bituminized web materials and method of and apparatus for making the same, there is disclosed a method of impregnating felt so that it is filled with two types of bituminous material, the core or inner part of the felt being impregnated with a relatively soft bituminous saturant and a surface layer of substantial depth of the felt being impregnated with a bituminous coating material of substantially higher softening point than the softening point of the saturant. According to this invention, a felt so prepared is caused to have adherent directly to one portion of the outer surface of the bituminous coating material a sheet or layer of one character and appearance and to have adherent directly to another portion of the said outer surface of the bituminous coating material a granular material which is of different character and appearance from said sheet or layer and which is adapted for the ornamental marginal portion of the siding strip. In this way, the coating material is keyed into the felt foundation of the siding strip and the softer saturant at the core of the felt is prevented from bleeding to the surface of the felt so as to form what is in effect a lubricant over the felt; and since both the ornamental marginal material and the contrasting material, e. g., sheet material, are directly adherent the coating material which is keyed to the felt, a siding strip is afforded which has the combined properties of improved ornamental quality and of being non-sliding in all parts thereof.

For the purpose of affording an illustration of the practice of this invention one method of mak-

ing a preferred form of siding strip embodying this invention will be described in connection with the accompanying drawing, wherein

Figure 1 is a schematic representation of one form of apparatus whereby siding strip may be manufactured according to this invention;

Fig. 2 is a plan view of a sheet of web material coated alternately with ribbons of sheet material and with coatings of granular material prior to the cutting of the same into siding strips;

Fig. 3 is a perspective view of a portion of siding strip embodying a preferred form of this invention with a part thereof magnified;

Fig. 4 is a sectional view of the siding strip taken on the line 4-4 of Fig. 3 with a part thereof magnified; and

Fig. 5 is a perspective view of a wall covered with siding strip embodying this invention and illustrating one form of ornamental design produced thereby.

Referring to the drawing, a sheet of felt or other web material 10 is taken from any suitable source not shown over roller 11 to saturating tank 12 where it passes alternately over rollers 13 below the surface of the saturant 14 in tank 12 and rollers 15 above the surface of the saturant. After passing from saturating tank 12 and prior to passing over roller 16 the web of material is passed between doctor blades 17 which remove excess saturant from the web. The saturated web is then coated with coating material 18 in coating tank 19 as described in the aforesaid Patent No. 2,105,531 by passing the same from guide roller 25 to squeeze rollers 20 which are between guide rollers 21 and 22 and 35 which compress the web 10 therebetween while it is submerged beneath the surface of coating material 18 so as to devoid the web by compression and permit the web to expand while submerged in the coating material so as to become coated and sealed in a devoided condition. Excess coating material is removed from the web by doctor blades 23 between guide roller 22 and guide roller 24 above the surface of coating material in tank 19. Coating material 45 is applied to the web from pipe 26 and is spread to desired thickness by spreading rollers 27.

By the method and apparatus above described the web material is thoroughly filled with saturant and is sealed in a devoided condition with 50 coating material as described in application Serial No. 681,286, above mentioned. The bituminous coating material penetrates the felt to substantial depth as a continuous and uniform layer of substantial thickness so that it is firmly keyed 55 to the felt.

The bituminized web material is now passed from roller 24 to roller 28 and receives one or more ribbons of paper or other sheet material 29 from one or more rolls 49. The ribbons of paper 60 29 or other sheet material may be of any desired width depending upon the area of web 10 which it is desired to have covered by the sheet material. While it is not essential to the practice of this invention, the paper 29 may be firmly impressed 65 against the web 10 by means of one or more rollers 30. The roller or rollers 30 which are on the same side of the web 10 as the paper 29 preferably correspond in width to the width of the ribbon or ribbons 29 so that the same will not 70 come into contact with the part of the web 10 that has not been covered with paper.

The web 10 is passed under a hopper 31 adapted to apply a granular material 38, for example, of desired color to the bituminized web 10. As the 75

ribbon 29 which has already been applied to the web has a substantially non-adhesive exposed i. e., outer surface, the granular material adheres only to those portions of the web which have not been covered with sheet material 29. The non-adhesive characteristics of the outer surface of the ribbon 29 of sheet material should be such that the granular material will not substantially adhere thereto. The inner surface of the ribbon 29 adheres to the web 10 by a suitable adhesive and may or may not be adhesive prior to application to the web 10. The web 10 is now passed over rolls 28, 32 and 33. In passing between rolls 28 and 32 the web receives on the back thereof an application of a finely divided material 39 such as mica flakes, for example, from hopper 34. Any other suitable separating material may also be employed. While it is not essential to the practice of this invention the web of material may be passed between rollers 35 to press the granular and finely divided material into the bituminous coating material on web 10 and cause the same to strongly adhere thereto. The web 10 is cooled by passing the same over any number of cooling rolls 36 and if desired can be passed between final press rolls 37.

In Fig. 2 there is illustrated a specimen web 10 having sheet and granular material adherent thereto.

30 The sheet material 29 is flanked on either side by the granular material 38. As thus made up the web base is adapted to be cut along longitudinal lines 40 to produce strips having granular surfacing material along and adjacent one margin thereof and sheet material forming the surface along and adjacent the other margin thereof. The web base may also be cut along lateral lines 41 so as to produce strips of any desired length. Moreover, the laterally extending holes 40 or cut-out portions 42 may be punched out as indicated by the lines 42 in Fig. 2. The cut-out parts 42 are preferably punched at more frequent intervals than the cuts 41 so that each siding strip may include a plurality of portions representing bricks, for example, spaced from each other by the cut-out portions 42.

Any suitable cutting and punching mechanisms may be employed. In Fig. 1 means for cutting this web 10 longitudinally is indicated generally by the reference character 43. Means for cutting the web 10 laterally and punching openings therein is indicated diagrammatically by the reference character 44.

A specimen of a siding strip embodying this invention is shown in Figs. 3 and 4. The strip comprises a web 10 impregnated with a bituminous saturant 14. The web is impregnated adjacent the surface thereof with bituminous coating material 18. Thus the web comprises a layer of felt impregnated with saturant and another layer of felt impregnated with coating material, the felts of the two layers being interfelted. Preferably also, a layer of coating material 45 overlies the web 14. The paper or other sheet material 29 adheres to coating 45. The granular material 38 also adheres to the coating 45 at points not covered by paper 29. Thus the web base has granular material adherent thereto by virtue of bituminous adhesive material directly interposed between the web base and granular material. Also the web base has sheet material adherent thereto by virtue of the said bituminous adhesive material also directly interposed between the sheet material and the web base. The back of the strip may be coated with a thin coating of finely

divided material 39, such as mica flakes to prevent the strips from sticking during shipment.

The appearance of the siding strip when manufactured to simulate brick, for example, and secured to the wall 47 of a building is shown in Fig. 5. The granular material 38 gives the appearance of the faces of bricks. The sheet material 29 shows between spaced portions coated with granular material 38 and gives the appearance of mortar between faces of bricks. The strips may be of any desired length and contain any number of separated lengths of granular surfacing material 38. Moreover, the web may be cut into separate shingles. The ends 46 of the strips may be cause to abut each other as shown. The strips may be affixed to the wall 47 as by nails 48.

The siding strip embodying this invention is seen to have the following advantages. The line between the paper or other sheet material 29 and granular material 38 is very sharp giving a neat appearance to a wall covered with the siding strip. The granular material 38 is more prominent with respect to the felt base than the paper 29 thus giving a desired effect that makes a wall covered with the siding strip have a highly realistic appearance. At the same time no part of the strip has more than one layer of material overlying the coating material and the coating material impregnates the web base of the strip to substantial depth so as to be keyed thereto. Thus the tendency of the materials overlying the web base to slide with respect to the web base is reduced to a minimum if not eliminated altogether. This tendency to slide has been a very serious defect in siding strip heretofore made. As the siding strip has only a small part thereof covered with granular material, great economy is effected with respect to the amount of granular material that is used. Moreover, the necessity for coating granular material with overlying layers of bituminous coating material is eliminated with resulting economy of bituminous materials that are used and of manipulations necessary in manufacturing the siding strip.

While mention has been made of the employment of paper in the manufacture of siding strip embodying this invention, it is to be understood that this has been done merely for the purpose of illustration, as any paper, felt, fabric or sheet of material may be employed according to this invention. It is preferable to employ sheet material which is impregnated with a material that renders the paper weather-resistant. Such paper is referred to herein as weatherproofed. Thus a paper that is saturated and/or coated with a relatively non-adhesive bituminous material is desirable for use in practicing this invention. The paper may or may not be coated with mineral surfacing material. Moreover, the color of the sheet material that is used can be varied as desired to produce different effects such, for example, as the effects resulting from the use of mortars of different colors. While sheet material is preferably employed according to this invention it is not without the scope thereof to employ other materials adhering to a web of material coated with adhesive material. For example, aluminum foil or other thin sheet metal could be used instead of paper for the production of certain effects.

It is also to be regarded as coming within the scope of this invention to afford a preformed ornamental sheet building covering such as siding strip comprising a web base, a first colored substance adherent to said web base by virtue of

an adhesive material penetrating said web to substantial depth and directly interposed between the web base and the colored substance and a second colored substance also adherent to the web base by virtue of an adhesive material penetrating said web to substantial depth and directly interposed between the web base and the second colored substance, the colored substances forming portions of contrasting colors of the ornamental surface of the building material. The employment of granular and non-granular materials of contrasting color thus directly adherent to a web base and forming different portions of the surface that is normally exposed to view when a plurality of the preformed units are secured in place to form parts of an ornamental design is also to be regarded as coming within the scope of this invention.

While mention has been made of the use of felt as a web material other web materials may also be used such as woven materials. Moreover, while the use of bituminous saturants and bituminous adhesive coatings for web materials has been mentioned as preferable, other adhesive coatings for a web may be used such as rubber latex, shellac, varnishes and the like. The term granular material should also be construed as including any granular or finely-divided solid material adapted to adhere to an adhesive material and form a coating for sheet building covering of the character described.

In the manufacture of siding strip using bituminous saturating and coating materials, it is usually preferable to employ usual types of shingle saturant and coating materials. For example, saturant having a softening point of 95° F. to 140° F. (as determined by the ball and ring method (and having a penetration of about 10 to 30 at 77° F. as determined by a Dow penetrometer, may be employed. Considerable latitude is permissible, however, as satisfactory results also result when the saturant has a softening point of about 75° F. to about 200° F. and a penetration of about 5 to about 200 at 77° F. The saturant is preferably applied at a temperature of about 350° F. to about 400° F.

The bituminous coating material preferably has a softening point between about 200° F. and about 250° F. and has a penetration of about 9 to about 20 at 77° F. However, satisfactory results are also obtained when the softening point ranges from about 190° F. to about 275° F. and the penetration ranges from about 50 to 5 at 77° F. The coating material is preferably applied at about 425° F., although about 50° F. to about 75° F. variation from this figure will still afford satisfactory results.

In manufacturing the bituminized web and coating the same with a granular material the portion of the siding strip which is surfaced with the granular material should preferably be made so that the weight of the bituminous coating material and solid granular material overlying the web material is less than about 45 pounds per 100 sq. ft. so as to minimize the tendency

of the overlying material to slide. However, if the weight of bituminous coating material is less than 15 lbs. per 100 sq. ft. and large, heavy granules are applied, it is practicable to increase the total weight of material overlying the web somewhat without inducing a tendency to slide.

While this invention has been described in connection with certain specific illustrations thereof it is to be understood that this has been done for the purpose of illustration merely and this invention is to be limited only by the scope of the following claims.

I claim:

1. A method of making siding strip which comprises saturating a web material with a bituminous saturant, immersing the web of material in a bath of bituminous coating material having a higher softening point than said saturant, compressing the web to devoid same and permitting it to expand while submerged in said bituminous coating material thereby impregnating said web with a continuous uniform layer of substantial depth in said web of said coating material, removing excess coating material from the surface of said web, applying adherently to said coating material while it is adhesive a paper having a substantially non-adhesive outer surface, applying adherently to said coating material which is not covered by said paper while it is adhesive a granular material, and cutting said web into strips having granular material along and adjacent the surface of the margin thereof and having paper along and adjacent the surface of the other margin thereof.

2. A method of making siding strip which comprises saturating a fibrous web material with a bituminous saturant, thereafter contacting the web material with a continuous deposit of bituminous coating material having a higher softening point than the softening point of said saturant, the said web material being squeezed to substantially reduced thickness to devoid same and then caused to expand while contacted with said bituminous coating material as aforesaid so as to become impregnated with a continuous layer of substantial depth in said web of said coating material, removing excess coating material from the surface of said web, applying granular material in spaced bands so as to adherently overlie said coating material, applying colored surfacing material the color of which contrasts with the color of said granular material so as to adherently overlie said coating material between said bands of granular material, and cutting said web into strips having said granular material along and adjacent the surface of a marginal portion thereof and having said material of contrasting color forming the surface of another portion thereof.

3. The process of claim 2 wherein the said squeezing of said web is progressive and said web is released from the squeezing while submerged in said bituminous coating material.

GEORGE ARTHUR FASOLD.
